CLAIM

The ornamental design for an electrode array, as shown and described.

DESCRIPTION

FIG. 1 is a perspective side view of the electrode array showing our new design;

FIG. 2 is a top plan view;

FIG. 3 is a bottom plan view thereof,

FIG. 4 is a front plan view thereof. The back plan view is substantially identical, and a duplicative back plan view is correspondingly not shown; and,

FIG. 5 is a left side plan view thereof. The right side is substantially identical, and a duplicative right side view is correspondingly not shown.

The broken line showing of the electrical coupling and the head of the human subject is included for illustrative purposes only and forms no part of the claimed design.
